UNITED STATES PATENT OFFICE

HARRY F. WOERNLEY, OF WILKINSBURG, PENNSYLVANIA, ASSIGNOR, BY MESNE ASSIGNMENTS, TO CARDWELL WESTINGHOUSE COMPANY, OF CHICAGO, ILLINOIS, A CORPORATION OF DELAWARE

FRICTION DRAFT GEAR

Application filed March 2, 1928. Serial No. 258,623.

This invention relates to draft rigging for railway cars and more particularly to friction draft rigging for use in passenger equipment cars.

When cars equipped with the usual friction draft rigging are coupled together in a train, the usual primary service shocks incident to the starting and stopping of the train are substantially wholly resisted through the operation of the friction elements of the draft riggings, and as these elements are not capable of cushioning such light shocks, a more or less rigid connection exists between adjacent cars, consequently these service shocks will be transmitted from one car to another, resulting in a very jerky action throughout the train, which is objectionable, for the reason that it causes discomfort to the passengers, causes unnecessary strains to be placed on the car parts and renders the operation of the train noisy.

The principal object of my invention is to provide a friction draft rigging for railway cars which will effectively cushion ordinary service shocks or strains incident to the operation of a train of coupled cars without bringing the friction elements of the draft riggings into operation, thus eliminating the objectionable features mentioned in the preceding paragraph.

Other objects and advantages will appear from the following more detailed description.

In the accompanying drawings: Fig. 1 is a longitudinal sectional plan view of the draft rigging, the several parts thereof being shown in their normal positions; Fig. 2 is a like view showing the several parts of the rigging in their initial cushioning positions, just prior to the operation of the friction elements; Fig. 3 is a like view showing the rigging fully compressed; Fig. 4 is a sectional view, like Fig. 1, of a modification of the invention; and Fig. 5 is a detail sectional view of Fig. 1.

The draft rigging shown in Figs. 1 to 3 inclusive of the drawings, may comprise a hollow rectangular casing 1 having front and rear sections 2 and 3 respectively, which are secured together by bolts 4 or any other

desired means. The front section 2 contains alternated friction plates 5 and 6 which are disposed at opposite sides of a wedging mechanism, the plates 5 being wedge shaped and anchored to the section 2 and the plates 6 having parallel friction faces. Under extraordinary draft strains the casing and plates 5 are movable relative to the plates 6 and under extraordinary buffering stresses the plates 6 are movable relative to the casing and plates 5.

Contained in the section 3 are springs 7 and 8, the rear ends of which seat on a movable spring seat or follower member 9 having a central portion 10 which normally extends through an opening in the rear wall 11 of the section and abuts a rear follower 12, which is engaged by the rear portion of a draft yoke 13. If desired, the member 9 and rear follower 12 may be made integral.

The forward end of the spring 7 seats on a shoulder or stop 14 which the rear end of the section 2 of the casing forms, and also seats on the inner ends of the friction plates 6, the front ends of these plates 6 abutting a front follower 15. This follower passes between the sides of the draft yoke and normally abuts front draft lugs or stops 16 which may be secured to the draft sills (not shown) of the car in the usual manner. The forward end portion of the yoke is attached to the butt 17 of the coupler, which butt normally abuts the front face of the follower 15. The rear follower 12 normally abuts against rear draft lugs or stops 18 which, like the front draft lugs, may be secured to the draft sills.

The wedging mechanism, hereinbefore referred to, comprises longitudinally disposed wedge blocks 19 and 20 having opposed wedging faces adapted to engage corresponding wedging faces of wedge blocks 21 and 22, the outer faces of said blocks 21 and 22 frictionally engaging the plates 5. The outer end of the wedge block 19 is engaged by the rear face of the front follower 15 and has a rearwardly extending stem 23, the rear end portion of which is loosely mounted in a recess 24 formed in the wedge block 20.

The wedge block 20, rearwardly of its

wedging faces, is provided with shoulders 25 upon which the forward end of the spring 8 seats, and is also provided with a rearwardly extending spring guide or lug 26 5 which the spring 8 surrounds.

The spring 7 is held under initial compression by the shoulder 14 of the section 2 of the casing and the spring 8, and all of the working parts associated therewith are 10 locked under initial compression, through the medium of a key 27 which extends vertically through slotted openings in the top and bottom walls of the section 2 of the casing and through an opening in the stem 23, 15 the slotted openings in the casing permitting relative movement between the casing and the key.

To prevent accidental endwise movement of the key 27, a pin 28 is provided, which extends through a longitudinal bore in the stem 23, and engages the key within a notch formed intermediate the ends of the key, which pin is held in this position by the pressure of a spring 29 contained in the recess 24 25 in the wedge block 20.

In the present embodiment of the invention, the plates 5 are provided with top and bottom extensions 30 which, as shown in Fig. 5 of the drawings, may extend into openings 30 formed in the top and bottom walls of the section 2 of the casing, the vertical edges of the extensions being adapted to engage the casing, thus anchoring the plates to the casing so that there will be no undue relative 35 longitudinal movement between the casing and the plates.

In operation, when the draft rigging is subjected to draft strains, the draft yoke 13, rear follower plate 12, and spring seat 9 are 40 moved forward, and the springs 7 and 8 compressed. These springs are preferably of such a capacity that they will resist and cushion ordinary shocks, incident to the pulling of the car. The wedging mechanism does 45 not assist in cushioning these ordinary draft shocks, for the reason that the plates 6, against which one end of the spring 7 seats, are maintained stationary by their cooperation with the front follower 15 which abuts 50 the front draft lugs 16.

Should the draft strain on the draft yoke be greater than can be wholly cushioned by the springs 7 and 8, the yoke will draw the rear follower 12 into operative engagement 55 with the rear wall 11 of the casing and then, through the medium of this follower, move the casing and the wedge shaped plates 5 forward as a unit. With this movement of the casing and plates 5, the plates 6 and wedge 60 block 19 remain stationary, due to their engagement with the front follower 15, which is in operative engagement with the front draft lugs 16. As this forward movement of the casing and plates 5 is continued, the lateral pressure of the friction elements of the

rigging is increased so that the frictional resistance between the elements is correspondingly increased. It will here be noted that as the plates 5 are wedge shaped, they will, when moved forward, force the wedge blocks 21 and 22 toward each other, and as the wedging faces of these blocks are in engagement with the wedging faces of the wedge block 19, which block is stationary, the blocks 21 and 22 will be moved rearwardly. The pressure of the wedge blocks 21 and 22 will also cause the wedge block 20 to move rearwardly against the pressure of the spring 8. It will further be noted that, as the ends of the plates 6 are abutted against the front follower 15, the forward movement of the casing and spring seat or follower member 9 will further compress the springs 7 and 8.

In releasing the rigging the pressure of the springs 7 and 8 acts upon the spring seat 9 to move said seat, follower 12 and draft yoke 13 rearwardly until said seat engages the inner face of the rear wall 11 of the casing, when the pressure of both springs acting through the follower member 9 will cause the casing and plates 5 to move rearwardly as a unit, thus relieving the pressure on the wedge blocks 21 and 22, permitting the pressure of the spring 8, through the medium of the wedge block 20, to move the blocks 21 and 22 forward to their normal positions as shown in Fig. 1 of the drawings.

When the draft gear is subjected to buffing stresses, the casing, together with all of the friction elements, are first moved rearwardly as a unit, and as the member 9 remains stationary, being abutted against the rear follower 12, which in turn abuts the fixed rear draft lugs 18, there will be a preliminary relative movement between the casing and the member 9, which movement may continue until the rear wall 11 of the casing engages the rear follower 12. If the buffing shock is too great to be absorbed by the springs 7 and 8, the friction plates 6 and wedge block 19 will be moved rearwardly by the front follower 15, when substantially the same wedging action, as hereinbefore described in connection with the draft strains, will take place.

In releasing the gear after buffing, the pressure of the springs 7 and 8 acting on the plates 6 cause the casing, all of the friction elements and front follower 15 to move forward as a unit until the rear end of the casing engages the member 9, when the pressure of the spring 7 will force the plates 6 and front follower 15 forward relative to the casing and plates 5 until the follower 15 engages the front draft lugs 16. At the same time the pressure of the spring 8 will cause the wedging mechanism to operate to relieve the lateral pressure on the plates 5 and 6 and casing 1.

In Fig. 4 a modification of the invention

has been illustrated in which the casing 1 is a single integral member, and in which the spring 7 seats on the inner ends of the plates 5 and 6 instead of directly on the casing and 5 on the plates 6 as illustrated in Figs. 1 to 3 inclusive. By making the casing in one piece the manufacture and repair of the rigging is facilitated, in that all of the parts may be inserted in, or removed from, the front end 10 of the casing. As the plates 5 are anchored to the casing 1 the operation of the draft rigging is substantially the same as the rigging hereinbefore described.

While two illustrative embodiments of the 15 invention have been described in detail, it is not my intention to limit its scope to these embodiments or otherwise than by the terms of the appended claim.

Having now described my invention, what 20 I claim as new and desire to secure by Letters Patent, is:—

In a shock absorbing mechanism, the combination with a casing, of friction elements in said casing, a stem projecting rearwardly 25 from one of said elements, a key extending through said stem and casing, a pin in said stem for locking said key and means interposed between said pin and another of said elements for holding said pin in locking engagement with said key.

In testimony whereof I have hereunto set my hand.

HARRY F. WOERNLEY.
